CLAIM

The ornamental design for a display screen or portion thereof with animated card communication, as shown and described.

DESCRIPTION

FIG. 1 is a front view of a display screen or portion thereof with animated card communication interface showing a first image in a sequence;

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The appearance of the animated images sequentially transitions between the images shown in FIGS. 1 through 7.

The process or period in which one image transitions to another forms no part of the claimed design.

The broken lines showing a display screen or portion thereof and all other broken lines showing portions of an animated card communication interface shown in FIGS. 1 through 7 illustrate environmental subject matter and form no part of the claimed design. The broken lines forming an electronic
